UNITED STATES PATENT OFFICE

161,948

COMBINATION SINK AND DRAIN RACK

Anna McGowan, Jackson Heights, N. Y.

Application April 27, 1950, Serial No. 9,515

Term of patent 14 years

(Cl. D4—2)

To all whom it may concern:

Be it known that I, Anna McGowan, a citizen of the United States of America, residing at No. 35-20 82nd Street, Jackson Heights, county of Queens, and State of New York, have invented a new, original, and ornamental Design for a Combination Sink and Drain Rack, of which the following is a specification, reference being had to the accompanying drawing, forming part hereof.

In the drawing:

Fig. 1 is a top plan view of the combination sink and drain rack, showing my new design;

Fig. 2 is a side elevational view thereof; and Fig. 3 is a perspective view thereof.

I claim:

The ornamental design for a combination sink and drain rack, substantially as shown.

ANNA McGOWAN.
